EGG CASE FILLER MACHINE

Application filed November 15, 1928, Serial No. 319,479. Renewed December 22, 1930.

This invention relates to egg case filler machines, and its principal object is to provide an automatic machine for forming the interlocking strips that comprise the cross walls of fillers for egg cases, and also cartons, and assembling said strips into the completed article. Another object is to provide automatically operating mechanism for slitting the material of which the fillers are made into strips; forming slots in certain of the strips and notches in the others; grouping the slotted strips into the spaced relation they occupy in the completed egg case filler; inserting the notched strips through the slots of the slotted strips, and severing the completed filler from the unassembled notched strips. Another object is to provide an egg case filler machine which requires no manual operation whatsoever and which is rapid and highly efficient in operation.

With these and other objects and advantages in view, this invention consists in an egg case filler machine having automatic mechanism for punching and slitting sheets of material into strips and assembling the strips into complete egg case fillers. It further consists in a novel arrangement of dies for punching out the slots and notches in the sheets combined with feed mechanism for the notched strips, sheet slitting or severing mechanism for dividing the sheets into strips, and mechanism for inserting the notched strips into the slots of the slotted strips.

It further consists in the provision of timing mechanism between the various elements that operate upon the material for co-ordinating the movements of said elements, whereby the notched strips may be properly inserted into the slots of the slotted strips.

The invention further consists in the several novel features of construction, arrangement and combination of parts hereinafter fully set forth and claimed.

The invention is clearly illustrated in the drawings accompanying this specification in which—

Figure 1 is a view, partly in front elevation and partly in vertical cross section, of an egg case filler machine embodying one form of the present invention;

Fig. 2 is a side elevation thereof with certain portions partly broken away;

Fig. 3 is a view partly in plan and partly in horizontal section, the section being taken on the line 3—3 of Fig. 2;

Fig. 4 is a detail vertical section of a certain clutch mechanism taken on the line 4—4 of Fig. 1;

Fig. 5 is a detail view, partly in plan and partly in horizontal section, of certain feed roll actuating mechanism, the section being taken on the line 5 of Fig. 2;

Fig. 6 is a detail section of a certain clutch mechanism taken on the line 6 of Fig. 2;

Fig. 7 is a detail view partly in plan and partly in horizontal section, taken on the line 7—7 of Fig. 6;

Fig. 8 is a detail horizontal section through the slitting mechanism for the notched strips taken on the line 8—8 of Fig. 2;

Fig. 9 is a view partly in side elevation and partly in vertical longitudinal section of the notched strip feeding mechanism and a fragment of the assembling frame, taken on the line 9 of Fig. 3;

Fig. 10 is a view partly in side elevation and partly in longitudinal section of certain members of the actuating mechanism for the feed mechanism seen in Fig. 9, the line of section being taken at 10—10 of Fig. 3;

Fig. 11 is a detail side elevation of the individual severing mechanisms for one of the notched strips, the strip being shown in cross section, and the section being taken on the line 11—11 of Fig. 9;

Fig. 12 is a view partly in end elevation and partly in vertical cross section of the assembling frame and actuating means therefor, the section being taken on the line 12—12 of Fig. 3;

Fig. 13 is a view similar to Fig. 12 with certain parts removed and showing the two members of the assembling frame separated from each other to permit the assembled egg case filler to be discharged therefrom;

Fig. 14 is a detail vertical section of the severing mechanism and feed mechanism for the slotted strip, the section being taken on line 14—14 of Fig. 3;

Fig. 15 is a detail side elevation of the feed

and bending rolls for one of the notched strips, the strip being shown in cross section, and the section being taken on the line 15—15 of Fig. 9;

5 Fig. 16 is a perspective view of a completed egg case filler constructed and assembled in a machine embodying the present invention;

10 Fig. 17 is a side elevation, partly broken away, of one of the slotted strips seen in Fig. 16, and showing one of the notched strips in cross section;

Fig. 18 is a side elevation, partly broken away, of one of the notched strips; and

15 Fig. 19 is a fragmental side elevation of one of the slotted strips and showing one of the notched strips in the position occupied by it while being assembled with the slotted strips.

As an example of an egg case filler, or other cardboard structure which may be made in 20 a machine embodying the present invention, the one shown in Fig. 16 of the drawings is illustrative. In this type of egg case filler, the parallel cross walls which extend in one direction contain the slots *s*, and the parallel 25 cross walls which intersect the first mentioned cross walls are formed with the opposing notches *n* in their opposite edges. The notched strips intersect the slotted strips at places where the notches are located, and by 30 making the distance between the upper and lower notches approximately the same as the distance between the upper and lower edges of the slots, the notched strips may be inserted through the slots by bending or bowing 35 them to conform to the curved edges of the slots and allowing them to spring back into a flat condition with the notched portions straddling the edge portions of the slotted strip. An interlocking condition is 40 thereby provided between the intersecting strips.

In order that the details of construction shown and described herein may be clearly understood, I shall first proceed to explain 45 the general construction and operation of the machine. Two long sheets of cardboard or other suitable egg case filler material, one for the slotted strips and one for the notched strips, are fed through the machine in an 50 intermittent manner by suitable feed mechanism, and upon entering the machine, one of the sheets is struck up with suitable dies to form the slots therein, and the other sheet is struck up with suitable dies to form notches 55 and elongated slots that subsequently become the notches. The two sheets run parallel to each other in the machine until they reach positions adjacent an assembling frame. However, before the sheet, from which the 60 notched strips are formed, reaches the assembling frame, it encounters a series of knives or cutting disks which slit the sheet into lengthwise extending ribbons or strips, and the free ends of said ribbons or strips are 65 thereafter bent upon themselves along their

length to form bowed or trough-like parts, all of which, except one, face in one and the same direction.

The sheet containing the slots is fed into a position above the assembling frame where 70 said sheet is slit transversely to provide a plurality of transversely extending slotted strips which are inserted into the assembling frame, and while being inserted thereinto, they are turned upon their axes so as to stand 75 crosswise of the assembling frame spaced apart and in parallel relation to each other with the slots of each strip in alignment with the slots of the other strips, after which the bent or trough-like end portions of the 80 notched strips are fed through the slots of the transversely extending slotted strips. Thereafter, the assembled notched strips are severed from the unassembled notched strips and the completed egg filler is discharged 85 from the assembling frame.

The assembling frame is made in two sections opening outwardly from each other, whereby when the bent notched strips are released by the assembling frame they 90 straighten out, due to their inherent resiliency, and interlock with the slotted strips. During the interval that the severed slotted strips are being fed into the assembling frame another length of the slotted sheet is fed into 95 the space formerly occupied by the severed slotted strips, and as the strip inserting means and strip slitting means for the slotted sheet is retracted, the newly fed portion of the slotted sheet is severed into individual slotted 100 strips for another filler.

Referring now to the drawings which illustrate one embodiment of the invention, and first to Figs. 1, 2 and 3, the reference character 20 designates the base of the machine 105 which, as shown, is mounted upon legs 21. As shown in the drawings, three separate units *a*, *b* and *c* (see Fig. 1) are provided in the one machine, and, inasmuch as these units are substantially alike, a description of one 110 unit will suffice for all.

Upon the upper and lower frame members 22 and 23 are bearing brackets 24 in which is journaled an upright die actuating shaft 25 which comprises the main driving shaft of 115 each unit, and upon the upper end of said shaft is a gear wheel 26 which may be clutched to the shaft 25 by a suitable clutch 27 (see Fig. 4). Secured to or formed as a part of said gear wheel 26 is a beveled gear 120, wheel 28 which meshes with a beveled pinion 29 fast upon a shaft 30 journaled in bearing brackets 31 mounted upon an upright frame 32. Upon the shaft 30 is a pulley 33 which may be driven from any suitable source of 125 power, and, as here shown, is belted to the pulley 34 of an electric motor 35 by a belt 36. It will be understood that each of the units *a*, *b* and *c* contains a die actuating shaft 25 and a gear wheel 26 thereon, and idlers 130

26* are provided between the gear wheels 26 which intermesh with said gear wheels and thus transmit power from the first mentioned shaft 25 to the corresponding shafts 5 25 of the other units.

The sheet from which the slotted strips are formed is illustrated at A and the sheet from which the notched strips are formed is shown at B. As shown in the drawings, the 10 sheet A runs parallel with the sheet B and is arranged thereabove. The sheets A and B may be fed from large rolls of filler material.

Adjacent the receiving end of the machine are the dies for punching the slots and 15 notches in the sheets. The stationary dies for the two sheets are shown at 37 and 38, said dies being mounted upon upright members 39 of the frame, and the movable dies 40 and 41 are carried by die heads 42 and 43 20 guided in suitable guideways 44 mounted on the frame.

The heads 42 of the movable dies are actuated by the shaft 25, and are here shown as 25 connected to operating struts or connecting rods 45 which have straps 46 upon their free ends that surround eccentric blocks 47 mounted upon the shaft 25. The movable die 40 carries a multiplicity of punches 48 which co-operate with openings 49 in the stationary 30 die 37 to form the slots s in the sheet A, and the movable die 41 carries a multiplicity of punches 50 which co-operate with openings 51 in the stationary die 38 to form notches n and other elongated holes n' in the sheet B, 35 which holes finally become notches in the notched strips, as will be hereinafter explained. The punches of both dies are arranged in rows extending at right angles to each other, certain of which extend lengthwise of the sheets A and B and the others of which extend at right angles thereto, as is 40 clearly seen in Fig. 2.

The machine illustrated in the drawings is 45 arranged to form the material and assemble an egg case filler containing thirty-six cells made up of seven slotted strips and seven notched strips extending through and interlocked with the slotted strips. Consequently, the die 40 contains seven punches for 50 the slots in each vertical row and the die 41 contains eight punches for the notches extending in each vertical row. It will be observed that the number of punches depends upon the number of strips used in making up 55 an egg case filler.

In the machine illustrated in the drawings, the two dies 40 and 41 are actuated once for each cycle of operation of the machine, and, consequently, the dies contain the required number of punches for punching all 60 of the slots and notches in the strip required for one complete egg case filler at one operation. The punches at the upper and lower ends of the die 41 are designed to form 65 notches in the opposing edges of the sheet B,

which notches are of the required depth, and the intermediate punches of said die cut out elongated openings in the body portion of the sheet (see Fig. 2) which, when the sheet is slit into individual strips, become notches 70 of the same depth as those on the edges of the sheet. While the exact shape of the punches is immaterial to this invention broadly considered, the punches for cutting out the slots s (see Fig. 17) are shaped to correspond 75 with the said slots, and the punches for cutting out the notches are shaped to form the notches n (see Fig. 18), it being understood that the intermediate punches of the die 41 punch out holes of twice the length of the 80 notches n seen in Fig. 18.

Mounted in bearing brackets carried by the frame of the machine is a feed roller 52 which co-operates with a roller 53 to feed the slotted sheet A to the strip slitting and 85 inserting mechanism, which will be herein-after described, and said feed rolls are rotated in an intermittent manner in timed relation to the action of the dies and the operation of the strip slitting and inserting mechanism. The mechanism shown for intermittently rotating the feed rolls 52 and 53 is best 90 shown in Figs. 2, 3 and 5.

On the lower end of the die actuating shaft 25 is a crank wheel 54 which is connected to a 95 lever 55 by a link 56, and the lever 55 is connected to a rack bar 57 by a link 58. The lever 55 is fulcrumed upon the underside of the frame of the machine and the rack bar 57 is slidably guided in a guide member 59 also 100 supported upon the underside of the frame. Meshing with the rack bar 57 is a pinion or other toothed wheel 60 which is loosely mounted upon an upright shaft 61 journaled in bearings carried by the frame of the machine, and ratchet clutch mechanism 62 (see also Figs. 6 and 7) is provided between the pinion 60 and the shaft 61, which ratchet mechanism is constructed and arranged to clutch the pinion to the shaft whenever the 105 rack bar 57 is moved in the direction of the arrow thereon in Fig. 5, but not when the rack bar is moved in the opposite direction. The feed rolls are timed so as to rotate while the punches are free from the stationary 110 dies.

Upon the upper end of the upright shaft 61 and upon the lower end of the shaft 63 of the feed roll 52 are mounted sprocket wheels 64 around which is trained a sprocket 115 chain 65 for transmitting motion from the upright shaft 61 to the feed roll 52. It will be observed that the feed rolls remain stationary while the rack bar 57 is moving in a direction opposite to the arrow thereon in 120 Fig. 5, and during this interval of rest of the feed rolls, the sheet A is being slotted and the slotted strips are being inserted into the assembling frame. During the movement of the rack bar 57 in the direction of 125 130

the arrow thereon, the feed rolls 52 are rotated thereby advancing the slotted sheet and carrying a length thereof into position to be acted upon by the strip slitting mechanism and strip inserting mechanism.

Directly beyond the feed rolls 52 and 53 is the strip slitting mechanism and strip inserting mechanism for the slotted strips. As shown in Figs. 2 and 3, a reciprocating frame 19 66 is provided which is slidably mounted and guided upon vertical channel shaped guide bars 67 secured to and supported by the frame of the machine. Rotatably mounted in bracket arms 68 carried by the frame 66 are cutting disks or knives 69 (see Fig. 14) which co-operate with a vertically extending cutting plate or board 70 to sever or slit the slotted sheet A along spaced vertical lines into the slotted strips A'. 23 Supported upon the frame 66 and extending intermediate the cutting disks or knives 69 are strip inserting fingers 71 which are here shown in the form of flat springs bent up, as illustrated in Fig. 14, and each having 25 one end entering a vertical groove 72 (see Fig. 14) in the cutting board 70. During the interval that the slotted sheet A is fed into the position occupied when it is severed into strips, the frame 66 and the cutting disks 30 69 and strip inserting fingers 71 occupy a lowered position with the cutting disks and inserting fingers below the path of movement taken by the slotted sheet. This permits the sheet to be freely advanced into position contiguous with the cutting board 70. After the slotted sheet has been advanced into proper position, the frame 66 and therewith the cutting disks and strip inserting fingers are moved upwardly, the cutting disks being 35 40 moved across the sheet and cutting or slitting the same into the individual slotted strips A'. The strip inserting fingers, being formed of resilient material, move freely upward along the severed strips to a position 45 slightly above the upper edge thereof.

The means shown for reciprocating the frame 66 comprises a lever 73 fulcrumed upon the frame of the machine at 74 and connected to the frame 66 by a link 75 (see Figs. 2 and 3). A cam block 76 having a circumferentially arranged cam groove 77 therein, and co-operating with a stud 78 on the lever 73, is provided for actuating the lever to thereby reciprocate the frame 66. The cam block 55 76 is mounted upon an upright cam shaft 79 journaled in suitable brackets mounted upon the frame of the machine, and said shaft is driven from the die actuating shaft 25 by a sprocket chain 80 trained over sprocket 60 wheels 81 and 82 mounted upon the die actuating shaft 25 and cam shaft 79, respectively. The sprocket wheel 81 is keyed to the shaft 25 and rotates continuously therewith.

As has been heretofore explained, the main 65 drive gear wheel 26 (see Fig. 4) is loose upon

the shaft 25 and is clutched thereto by the clutch 27 which may comprise a clutch collar 84 slidably mounted on the hub of the gear wheel and having the clutch pins 27^a thereon which slide through the sprocket wheel 81 and enter sockets in the gear wheel 26. A clutch lever 83 is provided for clutching the shaft 25 to the gear wheel 26, and said clutch lever engages with the clutch collar 84. In case the material becomes jammed in any of the units, or in case any of the mechanisms thereof become disabled, the attendant may throw that unit out of action by moving the clutch lever 83 in the proper direction, thereby unclutching the shaft 25 of that unit from the gear wheel 26.

After the slotted strips A' have been formed, they are inserted into the assembling frame by mechanism which will now be described. Immediately below the lower edges of the slotted strips, and in position to receive them when the strip inserting fingers move them down, are chutes or guideways 85 which guide the individual slotted strips to the assembling frame, and said chutes or guideways are twisted upon themselves so as to bring their discharge ends into a position at right angles to their receiving ends.

The receiving ends of said chutes or guideways 85 are in alignment with each other directly under the position occupied by the slotted strips above them, and their discharge ends extend at right angles thereto and are parallel with each other, being spaced apart a distance equal to the spacings of the notched strips of the finished egg case filler. From this it will be observed that the sheet A, which has passed through the machine in one plane, is severed into individual strips, and the strips are deflected from said plane into parallel planes at right angles thereto, and in this latter relation, they are fed into the assembling frame which will be described presently.

Secured to the cutting board, above the path of travel taken by the sheet A, are guide fingers 85^a, one for each slotted strip A', and secured to the upper ends of the chutes 85 are guide fingers 85^b which serve to prevent the slotted strips from falling or bending forward from the cutting board while being inserted into the chutes 85 by the strip inserting fingers. The fingers 85^a also act as stops for engagement with the upper edge of the sheet, thereby preventing it from being moved upwardly when being slit by the strip slitting disks.

The strip inserting fingers move the slotted strips part way through the chutes or guideways 85, and supplemental strip inserting mechanism is provided for moving the strips from the guideways into the assembling frame. Above the assembling frame is a strip inserting rod 86 which occupies a position above and out of alignment with the

paths of movement taken by the slotted strips during the interval that the strips are being inserted into the chutes 85. Said strip inserting rod is carried by arms 87 mounted upon a 5 rock shaft 88 which is journaled in brackets carried by the frame of the machine, and driven from the cam shaft 79 in timed relation to the movements of the reciprocating frame 66.

10 As shown, the rock shaft 88 is equipped with a gear 89 thereon which meshes with a segmental rack 90 rotatably mounted upon a stud shaft 91. From the segmental rack 90 extends an arm 92 which bears a roller 93 that 15 co-operates with a cam groove 94 formed in the face of a cam block 95 which is mounted on the shaft 79. The arrangement of the parts just described is such that once during each complete rotation of the shaft 79, the 20 intermeshing segmental racks 89 and 90 are oscillated back and forth once and the arms 87 and therewith the strip inserting rod 86 are moved up and down once, whereby the slotted strips, which previously have been 25 moved down into position to be engaged by the strip inserting rod 86, are thereby fed into the assembling frame at right angles to the position they formerly occupied.

Immediately below the chutes 85 is the 30 assembling frame 96 (see Figs. 9, 12 and 13). Said frame comprises two companion sections 97—97 that have parallel vertically extending transversely arranged guideways 98 in alignment with the discharge ends of the chutes 35 85 for the reception of the slotted strips A' and parallel horizontally extending channels 99 of less width than the guideways and intersecting them. The channels act to 40 guide the notched strips through the slots of the slotted strips.

In the upper portion of the assembling frame (see Fig. 12) is illustrated one of the slotted strips A', and through each of the slots of said strip is shown one of the notched 45 strips B' in cross section, the notched strips, while contained in the assembling frame, being bent or curved along lines running lengthwise of themselves. The vertical guideways 98 are provided by forming deep grooves in 50 the opposing faces of the two sections 97.

The horizontal channels are provided by forming horizontally extending deep grooves in the opposing faces of the two sections 97. When the two sections are brought together, 55 as shown in Fig. 12, the companion horizontal grooves form the channels 99, which in cross section, correspond generally to the shape of the slots s in the slotted strip A. At the bottom of the two sections 97 are 60 shoulders 100, or other stops, for supporting the slotted strips A' in the assembling frame with the slots s of said strips in register with the channels 99. It will be understood, therefore, that when the notched strips B' 65 are bent or curved into a shape to correspond

with the curved walls of the channels 99, the notched strips may be inserted through said channels from end to end and consequently inserted through the slots s of the slotted strips A'.

Means are provided for bringing the two sections of the assembling frame together in position for receiving the slotted and notched strips and for separating the two sections, whereby the completed egg case filler may be discharged therefrom. As shown in the drawings, two operating shafts 101 are employed for actuating the two sections of the assembling frame, which shafts are journaled in brackets 102 carried by the frame of the machine, said shafts being connected so as to rotate in unison, as, for instance, by means of a sprocket chain 103 trained around sprocket wheels 104 mounted upon the lower ends of the shafts 101.

Operative connections are provided between the shafts 101 and the two sections 97 of the assembling frame which, as shown, comprise cam blocks 105 mounted on the shafts 101 and having cam grooves therein 90 co-operating with pins or studs 106 carried by the two sections of the assembling frame. The pins or studs 106 are illustrated as mounted on brackets 107 secured to the outer sides of the two sections 97. The two sections of the assembling frame are guided in horizontally extending guide members 108, whereby they move in a parallel line at right angles to their length.

The two sections are here shown as provided with shoes 109 which travel in the guideways of the guide members 108. It will be observed that during each complete rotation of the shafts 101, the two sections of the assembling frame are drawn apart 100 to discharge a completed egg case filler and moved together in position to receive the strips for assembling another filler. The cam grooves in the cam 105 contain concentric portions co-operating with the pins or studs 106 to permit the two sections of the assembling frame to remain in closed position during the major portion of one complete rotation of the shafts 101. The two sections are 105 separated only for such an interval of time 110 as will permit the completed egg case filler to drop out of the assembling frame. The shafts 101 are driven from the cam shaft 79 and rotate in timed relation to said shaft and the main die actuating shaft 25. As shown 115 in Figs. 2 and 3, the drive mechanism between the cam shaft 79 and the shaft 101 comprises a sprocket chain 110 trained over sprocket wheels 111 and 112, one of which is mounted on the cam shaft 79, and the other 120 on one of the shafts 101.

In order that each completed egg case filler may be effectively discharged from the assembling frame when the two sections thereof are moved apart, stationary horizon- 130

tal rods 113 are provided which extend through horizontal grooves 114 in the two sections 97 of the assembling frame. The rods 113 may be supported by any convenient part of the machine, and are arranged in two vertical rows in close proximity to the position occupied by the side edges of the slotted strips. It is to be observed by reference to Figs. 12 and 13 that when the two sections 10 of the assembling frame are moved apart to release the completed egg case filler therefrom, the rods 113 engage the edges of the notched strips of the egg case filler, thereby stripping it from the assembling frame, and 15 when the supports 100 at the bottom of the two sections of the assembling frame have been moved from underneath the completed egg case filler, the latter drops between the opposing rods 113 and falls free and clear 20 of the two sections of the assembling frame.

Adjacent the die 41 which operates on the sheet B are cutting disks or knives 115 (see Figs. 2 and 8) which co-operate with a roller 116 to slit or sever the sheet B into individual 25 notched ribbons or strips B'. The cutting disks or knives 115 are mounted on a vertically extending rod 117 carried in a supporting bracket 118 adjustably mounted in a frame member 119 carried by the main 30 frame of the machine. Adjustment means is provided, as seen in Fig. 8, for fastening the bracket 118 to the frame member 119. The cutting disks or knives 115 are spaced equidistant and disposed in such relation to the 35 sheet B as to sever the same midway between the ends of each opening s', thereby forming the notches s in the ribbons or strips B'.

Means are provided for feeding the notched ribbons or strips B' into the assembling frame in timed relation to the other operating mechanism of the machine, and said feed mechanism is intermittently operated from the main or die actuating shaft 40 and is set into motion as soon as the slotted strips A' have been inserted into the assembling frame in position to receive the notched strips. Said feed mechanism is also arranged to turn the ribbons or strips B' along their horizontal axes from a vertical plane into spaced superposed horizontal 45 planes, and, at the same time, said feed mechanism is arranged to bend the notched ribbons or strips B' into trough-like configurations, in which condition they are inserted 50 into the assembling frame.

As shown, the feeding mechanism for each ribbon or strip B' comprises two companion rollers 120 and 121 (see Figs. 9 and 15), one of which is formed with a concave circumferential face and the other of which is formed with a convex circumferential face. The rollers are mounted upon shafts 122 and 123 journaled in frame members 124 carried by the main frame of the machine, and the rollers 121 are positively driven in an intermit- 55

tent manner by suitable drive mechanism which, as shown in the drawings, comprises pinions or toothed wheels 125 mounted upon the ends of the shafts 122 of the rollers 121 and meshing with a rack bar 126 (see also Fig. 10). The pinions or toothed wheels 125 are loose upon the shafts of the rollers, and ratchet clutch mechanism, similar to that shown in Fig. 6, is provided between the pinions and rollers, whereby motion will be transmitted from the rack bar to the shafts of the rollers only when the rack bar is being moved in one direction. 70

It is to be observed from Figs. 2, 9 and 10 that all of the feed rolls 120 and 121, with the exception of the uppermost set, are arranged to form the convex part of the trough-like configuration given to the notched ribbons or strips B', on the upper sides thereof, whereas the uppermost set of feed rolls is arranged to bend the uppermost ribbon in the opposite direction so as to have the convex side face in the opposite direction. 75

In order to rotate the roll 121 of the uppermost set in the proper direction to feed the uppermost ribbon or strip in the same direction as the remaining ribbons or strips are fed, the uppermost set of rolls and their driving pinion 125 are placed on the opposite side of the rack bar 126 (see Fig. 10) which is provided with rack teeth on both sides. It is to be observed from an inspection of Figs. 9 and 10 that when the rack bar 126 is moved upwardly, the feeding rolls are rotated in the directions of the adjacent arrows, and, consequently, the notched ribbons or strips A' are fed into the assembling frame, but that when the rack bar is moved downwardly, the feed rolls remain at rest, since the clutches between the pinions 125 and the roll shafts 123 operate to clutch the pinions and shafts together only when the pinions are moved in the one direction. 90

The rack bar 126 is guided upon the frame member 124, as, for instance, by a pin or roller 127 which engages in a slot 128 in the rack bar. The rack bar is reciprocated by the main shaft 25 in timed relation to the other mechanism of the machine by means here shown as comprising a bell crank lever 129 (see Fig. 5) fulcrumed upon the frame of the machine and connected to the crank wheel 54 by a link 130, link 58, lever 55 and link 56. 95

From the above, it will be understood that after the slotted strips A' have been fed into the assembling frame with the slots s in register with the channel 99 thereof, the bent or curved portions of the notched strips B' are fed into the channels of the assembling frame and through the slots of the slotted strips. The arrangement and proportions of the parts are such that the notched ribbons or strips are placed in the assembling frame with their notches n at the intersections with 100 105 110 115 120 125 130

the slotted strips, which position is illustrated in Fig. 19.

While the exact shape of the slots *s* is immaterial, the one shown enables the notched ribbons or strips to be readily inserted through the slots of the slotted strips and interlock therewith when released from their bent or bowed condition. The slots shown are of a configuration somewhat in the nature 10 of the letter **D**, the lateral extensions *s'* thereof permitting the edge portions of the notched ribbons or strips *B'* to enter the **D** slots when the notched ribbons or strips are maintained in their bent or bowed condition. It is to be 15 observed that when the notched strips are released from the bowed condition shown in Fig. 19, their inherent resiliency serves to straighten them out into the flat condition shown in Fig. 17, wherein the strips interlock 20 at the intersections with the slotted strips.

Severing means are provided for cutting the assembled portions of the notched ribbons or strips *B'* from the unassembled portions thereof, and, as shown, said severing means comprise companion knives 181 (see Fig. 11) secured to one end of the assembling frame, adjacent the ends of the channels 99 therein. Each knife is secured to one section 25 of the assembling frame and extends across the end of the other section and downwardly, as is clearly seen in Fig. 11. It is to be observed that when the two sections of the assembling frame are moved apart from the 30 position seen in Fig. 8 that the blades or knives 181 will sever the strips at the places where the knives pass across the same.

As the knives sever the assembled notched strips from the unassembled ones, the completed assembled egg case filler is free to fall 40 and does drop out of the assembling frame, as is clearly seen in Fig. 2. Conveniently, a conveyor 132 may be provided underneath the assembling frame for conveying the assembled egg case fillers away from the machine.

In the operation of the machine, the egg case filler material is acted upon by the dies adjacent the receiving end of the machine, 50 and the slots *s*, notches *n* and double notches *n'* are formed therein. During the interval that the strip inserting frame 66 occupies its lowermost position, the feed rollers 52 and 53 feed the slotted sheet *A* into position before said frame, and thereafter the cam 76 swings upwardly the arm 73, thereby lifting the frame 66, and during the upward movement of said frame, the cutting disks or knives 69 cut the adjacent portion of the 55 sheet *A* into individual slotted strips *A'*.

The cam 76 thereafter swings the lever 73 downwardly, thereby moving the frame 66 downwardly, whereupon the strip inserting fingers 71 force the strips part way through 60 the chutes or guideways 85 where they are

turned at right angles to their former position, after which the cam 95, through its connection with the arms 87, moves down the rod or bar 86, thereby forcing the slotted strips into the assembling frame in spaced relation to each other and at right angles to the position occupied before they were severed from the sheet *A*. 70

During the interval that the slotted strips are being fed into the assembling frame, the sheet *B* is at rest, but as soon as the slotted strips have been inserted into the assembling frame, the rack bar 126 is moved upwardly thereby rotating the feed rolls 120 and 121, and said feed rolls draw the sheet *B* towards the assembling frame, whereby the sheet is slit as it encounters the cutting disks 115 and 116. The ribbons or strips *B'* thus formed are turned into spaced superposed horizontal planes and bent or bowed upon themselves by the feed rolls 120 and 121, and the bent ends of the ribbons or strips *B'* are inserted into the channels of the assembling frame and through the slots of the slotted strips. 75 80 85

Immediately thereafter the two sections of the assembling frame are moved apart by the cams 105, during which time the knives 181 sever the assembled portions of the notched strips from the remainder of the ribbons *B'*. As the two sections of the assembling frame 90 separate, the bent or bowed notched strips straighten out under their inherent resiliency, whereby the notched portions interlock with the slotted strips and the completed egg case filler drops from the assembling frame 95 100 upon the conveyor which carries it away from the machine. 105

It is to be observed that all of the strips for making a complete filler may be slit from two sheets. This is a particular advantage, 110 since it requires merely the handling of two rolls of material. Furthermore, by running the two sheets through the machine with one sheet disposed above the other in a vertical plane, the punchings from the sheets fall away from the sheets and dies, and, consequently, do not interfere with the action of the dies. Moreover, the several units which comprise the complete machine may be timed to operate in some regular sequence, whereby the punching operations of each unit takes place when the punches of the other units are at rest. By reason of this arrangement, power is economized and the wear and tear of the machine is greatly lessened. 115 120

More or less variation of the exact details of construction is possible without departing from the spirit of this invention. I desire, therefore, not to limit myself to the exact form of the construction shown and described, but intend, in the following claims, to point out all of the invention disclosed herein. 125

I claim:

1. In a machine of the class described, the 130

combination with an assembling frame formed with two intersecting sets of guideways for the reception of material, of feeding and inserting mechanism entirely exterior of said guideways and operating to insert the material into the intersecting guideways of the assembling frame.

2. In a machine of the class described, the combination with an assembling frame formed with intersecting sets of guideways for the reception of the material, of feeding mechanism for the material, including two material inserting mechanisms, one operating to insert material into one set of guideways in the assembling frame and the other operating to insert material through the other set of guideways therein, said material inserting mechanism being entirely exterior of said guideways.

3. In a machine of the class described, the combination with an assembling frame having parallel transversely extending guideways therein and parallel D-shaped channels of less width than the guideways and intersecting the same, of material feeding mechanism including inserting mechanism entirely exterior of said guideways for inserting lengths of material into said guideways, and feeding mechanism entirely exterior of said guideways for inserting lengths of material into said D-shaped channels and through the material in the guideways.

4. In an egg case filler machine, the combination with an assembling frame comprising separable sections having parallel transversely extending guideways therein for the reception of slotted material and parallel channels of less width than the guideways and intersecting the same, said channels being adapted to receive notched material, of feeding mechanism for the slotted material, and inserting mechanism therefor arranged to insert lengths of slotted material into the guideways of the assembling frame, and feeding mechanism entirely exterior of said channels for feeding the notched material into the channels of said frames and through the slots of the slotted material, said sections separating from each other to discharge a complete filler therefrom.

5. The combination with an assembling frame having parallel transversely extending guideways for the reception of slotted strip material and parallel channels of less width than the guideways and intersecting the same, said channels being adapted to receive notched strip material of the same width as the slotted strip material, of material inserting mechanism for inserting slotted strip material into the guideways of the assembling frame, and means entirely exterior of said channel for inserting notched strip material of the same width as the slotted strip material into the channels of the as-

sembling frame and through the slots of the slotted strip material.

6. The combination with an assembling frame comprising separable sections having parallel transversely extending guideways adapted for the reception of slotted strip material and parallel channels of less width than the guideways and intersecting the same, said channels being adapted to receive notched strip material of the same width as the slotted strip material, of inserting mechanism for the slotted strip material, and notched strip feeding mechanism having means entirely exterior of said channels for bending the notched strip material to conform substantially to the channels in the assembling frame.

7. In an egg case filler machine, the combination with an assembling frame having spaced parallel transversely extending guideways therein and spaced parallel channels therein of less width than the guideways and intersecting the same, of intermittently operating sheet feeding rolls for one sheet of material, sheet slitting mechanism for slitting the sheet transversely to form individual strips, strip inserting mechanism for inserting the strips into the guideways of the assembling frame, other sheet slitting means for slitting another sheet into lengthwise extending strips of the same width as the first mentioned strips, and strip feeding mechanism for feeding said last mentioned strips into said channels and having strip bending elements whereby said last mentioned strips are shaped to conform to the channels of the assembling frame.

8. In an egg case filler machine, the combination of intermittently acting sheet feeding rolls, sheet slotting die mechanism, sheet slitting mechanism, an assembling frame, strip inserting mechanism entirely exterior of the assembling frame for inserting strips into the assembling frame, and operating mechanism for actuating said elements in timed relation to each other.

9. In an egg case filler machine, the combination of intermittently acting sheet feeding mechanism, punching dies operating upon said sheet, sheet slitting mechanism arranged to slit said sheet into individual strips, strip inserting mechanism, a separable assembling frame having intersecting guideways and channels therein into which said strips are inserted, said strip inserting mechanism being entirely exterior of said assembling frame, and operating means for actuating said elements in timed relation to each other.

10. In an egg case filler machine, the combination of intermittently acting sheet feeding mechanism, sheet slotting dies, slitting mechanism for slitting the sheet transversely to form individually slotted strips, an assembling frame having parallel transversely extending guideways therein, and strip feeding

mechanism including guideways for turning said strips out of their normal plane into individual planes at right angles thereto.

11. In an egg case filler machine, an assembling frame comprising two companion separable sections formed with parallel spaced transversely extending guideways therein for the reception of slotted material, and parallel spaced channels therein of less width than the guideways and intersecting the latter, said channels being adapted for the reception of notched material, and operating mechanism for opening and closing said frame.
12. In an egg case filler machine, the combination with an assembling frame, of intermittently operating sheet feeding mechanism, sheet slitting mechanism for slitting a sheet crosswise to form individual strips, strip inserting mechanism for inserting said strips into said assembling frame and including means for turning said strips from one plane into spaced parallel planes disposed at right angles thereto, and operating mechanism for actuating said feeding mechanism, slitting mechanism and inserting mechanism in timed relation to each other.
13. In an egg case filler machine, the combination of an assembling frame having parallel channels therein, of sheet slitting means for slitting the sheet along spaced lines running lengthwise of the sheet to form longitudinally extending strips, strip feeding rolls for each strip, said rolls rotating on axes disposed in planes at right angles to the plane of the sheet and having means for bending the strips into trough-like configurations conforming generally to the configuration of the channels in the assembling frame.
14. In an egg case filler machine, the combination with an assembling frame having spaced parallel guideways extending transversely therein and spaced parallel channels therein of less width than the guideways and intersecting the same, of feed mechanism for feeding two sheets of material to said assembling frame, sheet slitting means for slitting one of said sheets transversely and sheet slitting means for slitting the other sheet lengthwise of itself, strip inserting mechanism for the strips cut from the first mentioned sheet, and including means for turning said strips into spaced parallel planes at right angles to the sheet, other strip inserting means for the second mentioned strips having means for turning the end portions of said strips into parallel spaced planes and bending the end portions of said strips to conform generally to the shape of the channels in the assembling frame, and operating mechanism for actuating said elements in timed relation to each other.
15. In an egg case filler machine, the combination with an assembling frame having parallel spaced guideways therein, of sheet

punching die mechanism, intermittently operating sheet feeding rolls, a reciprocating frame movable transversely of the sheet, sheet slitting mechanism and strip inserting fingers carried by said frame, and guide chutes for the strips having receiving ends disposed in the plane of the severed strips and discharge ends disposed in the planes of the guideways in the assembling frame, and operating mechanism for actuating said movable elements in timed relation to each other.

16. In an egg case filler machine, the combination with an assembling frame having intersecting guideways and channels for the reception of strip material, of sheet slotting and sheet notching die mechanism, sheet feeding mechanism for advancing a sheet through the sheet slotting mechanism, sheet slitting mechanism operating to slit said last mentioned sheet transversely to form individually slotted strips, slotted strip inserting mechanism for inserting the slotted strips into the guideways of the assembling frame, sheet slitting means for slitting the notched sheet into longitudinally extending strips, and strip feeding means for feeding said last mentioned strips into the channels of the assembling frame, said last mentioned strip feeding means having concave faced rolls for bending said strips into trough-like configuration conforming with the channels of the assembling frame.

17. In an egg case filler machine, the combination with an assembling frame having spaced parallel guideways therein for the reception of strip material, of a reciprocating frame, cutting disks carried thereby, a cutting table co-operating with said cutting disks to sever sheet material into strips, and strip inserting mechanism carried by said reciprocating frame and arranged to insert the strips into said assembly frame.

18. In an egg case filler machine, the combination with an assembling frame having spaced parallel guideways therein for the reception of strip material, of sheet slitting disks arranged to slit sheet material into longitudinally extending strips, feed rolls rotating on axes disposed at right angles to the plane of the sheet, and having means for bending the strips into trough-like form conforming to the shape of the channels in the assembling frame.

19. In an egg case filler machine, the combination with an assembling frame having spaced parallel D shaped channels therein, of sets of co-acting feed rolls for feeding strip material into said channels, one roll of each set having a concave circumferential face and the other roll having a convex circumferential face.

20. In an egg case filler machine, the combination of co-acting strip feeding rolls having means for bending the strips into trough-

- like form, and means for intermittently rotating said feed rolls.
21. In a filler machine for assembling edge-notched walls with other walls having 5 D-slots therein, the combination of means for moving angularly to a point of assembly both sets of walls, the slotted walls first, and entirely exterior means for bowing and inserting the notched walls lengthwise through the 10 D-slots of the other walls.
22. In a machine of the class described, the combination of means for feeding two sheets of material from which individual slotted and notched strips are formed, means for assembling the slotted strips in spaced parallel relation, and other entirely exterior means for inserting the notched strips through the slots of the slotted strips.
23. The combination of means for feeding 20 two sheets of filler material, slotting and notching die mechanism for said filler material, sheet slitting mechanism for slitting said sheets into slotted strips and notched strips, means for assembling the slotted strips 25 in spaced parallel relation to each other, and other entirely exterior means for inserting notched strips into the slots of the slotted strips.
24. In a filler machine for assembling edge 30 notched walls with other slots having D slots therein, the combination of means for moving angularly to a point of assembly both sets of walls, the slotted wall first, a separable assembling frame for receiving said 35 notched walls and slotted walls, and means entirely exterior of said assembling frame for bowing and inserting the notched walls lengthwise through the D slots of the other walls.
- 40 25. In an egg case filler machine, the combination of acting sheet feeding rolls, sheet slotting die mechanism, sheet slitting mechanism, an assembling frame, strip inserting mechanism entirely exterior of said assembling frame for inserting strips into the assembling frame, and operating mechanism for actuating said elements in timed relation to each other.
- 50 26. The combination with material slotting and notching mechanism, of an assembling frame formed with two intersecting sets of guideways for the reception of material, and feeding and inserting mechanism entirely external of the assembling frame operating to insert the material into the intersecting guideways of the assembling frame.
- 55 27. In a machine of the character described, a vertically extending laterally separable material assembling frame having guideways for said slotted material and intersected by channels of less width than the guideways for receiving notched material, said assembling frame being capable of opening to discharge a completed filler therefrom.
- 60 65 28. In a filler forming and assembling ma-
- chine, the combination of material slotting and notching dies at the receiving end of the machine, material feeding and slitting mechanism, and a vertically extending laterally separable material assembling frame having intersecting guideways therein for receiving the material to be assembled, said assembling frame being capable of opening to discharge a completed filler therefrom.
- 70 29. In a filler forming and assembling machine, the combination of slotting and notching dies, material feeding mechanism for two sheets of material, sheet slitting mechanism, and a vertically extending laterally separable assembling frame having intersecting guideways therein into which the material is fed, said assembling frame being capable of opening to discharge a completed filler therefrom.
- 75 30. In a filler forming and assembling machine, the combination of means for feeding two vertically aligned material sheets through the machine, slotting and punching dies for said sheets and arranged in vertical alignment with each other, sheet slitting means, and laterally separable means having intersecting guideways wherein the slotted and notched strips are assembled.
- 80 31. In a filler forming and assembling machine, a laterally separable sectional assembling frame having vertical guideways for the reception of slotted material, and intersecting horizontal channels of less width than the guideways for the reception of notched material whereby, when the two sections of the frame are separated, the assembled filler is discharged in a vertical direction lengthwise of itself.
- 85 32. In a filler forming and assembling machine, the combination of several units all 90 driven from a main drive shaft and each comprising die mechanism, material feeding and slitting mechanisms, and strip assembling mechanism, the operations of the mechanisms of each unit following those of the other units in regular sequence.
- 95 33. In a filler forming and assembling machine, a laterally separable assembling frame 100 having intersecting guideways for the reception of slotted and notched material, said intersecting guideways being disposed in a vertical direction, said assembling frame being capable of opening to discharge a completed filler therefrom.
- 105 34. In a filler forming and assembling machine, an assembling frame comprising two laterally separable sections, there being intersecting filler receiving guideways in said frame disposed in a vertical direction whereby the assembled filler may be discharged 110 therefrom in a vertical direction.
- 115 35. In witness whereof, I have hereunto set my hand this 12th day of November, 1928.
- 120 125 130 E. JOSEPH KANABAY.
